UNITED STATES PATENT OFFICE.

CHARLES F. FREDE, OF ST. LOUIS, MISSOURI, AND ANDREW J. DINKEL, OF GRANITE CITY, ILLINOIS, ASSIGNORS TO BALANCED CHUTE DUMP CAR COMPANY, OF ST. LOUIS, MISSOURI, A CORPORATION OF DELAWARE.

DUMP-CAR-OPERATING MECHANISM.

1,126,972.

Specification of Letters Patent.

Patented Feb. 2, 1915.

Application filed August 18, 1913. Serial No. 785,412.

To all whom it may concern:

Be it known that we, CHARLES F. FREDE and ANDREW J. DINKEL, citizens of the United States, residing, respectively, at St. Louis, in the State of Missouri, and at Granite City, in the county of Madison and State of Illinois, have invented a new and useful Improvement in Dump-Car-Operating Mechanism, of which the following is a specification.

Our invention relates to mechanism for operating the drop doors of a dumping car, bin, storage elevator, or analogous receptacle, whether mounted on wheels or stationary, adapted to contain sand, earth, coal, ore, grain, or the like, and from which the contents are discharged or dumped through an opening in the floor controlled by the said doors to either side of and beneath the said receptacle, and our invention applies particularly to such a receptacle having two opposite side (outside and inside) doors hinged to and dependent from the floor and adapted to form when closed a V-shaped hopper beneath the said opening, combined with a pivoted balanced door or chute adapted to lock the side doors in their closed position and to form a chute thereto in their open position, such as the arrangement described and shown in the Letters Patent granted to Herbert L. Aulls, April 16, 1907, Number 850,719, for improvements in convertible dumping cars.

Our invention which is in the nature of an improvement on the Letters Patent granted to Charles T. Westlake, and Charles F. Frede, May 12, 1908, Number 887,163, for an improvement in dump-car-operating mechanism, has for its object to enable the balanced door or chute and one of the side doors to be opened consecutively in the order named, and held in the open position for discharging the contents of the car or receptacle to the corresponding side beneath the same, the other side door being simultaneously held in its normal or closed position, and to enable either of the side doors to be closed initially in advance of the balanced door or chute.

The invention consists in features of novelty as hereinafter described and claimed,

reference being had to the accompanying drawing forming part of this specification, whereon,

Figure 1, is a top plan view of one end and adjacent part of a dump-car having our improved door operating mechanism applied thereto, Fig. 2, an end elevation of the car frame (broken away) at one side of the vertical center of the car showing the corresponding complete set of the operating mechanism in side view with the doors in their closed or normal position; Fig. 3, a similar view to Fig. 2, with the balanced door or chute in position for holding the inside door closed while releasing and allowing the outside door to be opened; Fig. 4, a similar view to Fig. 2, with the balanced door or chute in the position seen in Fig. 3, and the outside door opened for dumping to the side of the car; Fig. 5, a side view to enlarged scale of the engaging parts of the controlling and operating levers (broken away) of the mechanism with their respective operating devices forming parts of our invention in the position seen in Fig. 1; Fig. 6, a vertical transverse section through the same on line 6, 6, in Fig. 5; Fig. 7, a horizontal section thereof on line 7, 7, in Fig. 5; Fig. 8, a similar view to Fig. 5 with the parts in position as seen in Fig. 3; Fig. 9, a vertical section through the reversing switch block forming part of our invention, on line 9, 9, in Fig. 6, looking to the left; Fig. 10, a similar view to Fig. 9, through the switch block on line 10, 10, in Fig. 6, looking to the right, and Fig. 11, a vertical cross section through the trip lever forming part of the locking device for the switch-block, on line 11, 11, in Fig. 7.

Like letters and numerals of reference denote like parts in all the figures.

a represents a dump-car having preferably, at each side thereof through the floor 1 a rectangular-shaped opening 2 for the discharge therethrough of the contents of the car *a*, the floor 1 at and between the openings 2 being inclined upward to a suitable height from the openings 2 for insuring the dump or discharge of the contents of the car by gravity through the openings 2 without shoveling or plowing.

Extending longitudinally through the car *a* at the inner and outer sides of each opening *2*, and rotatable in bearings *3* formed in or fixed to the floor *1* thereat, are 5 shafts *4*, and *4'*, respectively, to each of which is fixed a door *b* dependent from the floor *1* and having its upper longitudinal edge or member corresponding to, and in juxtaposition to the side of the opening *2*, 10 the two opposite doors *b* of each opening *2*, on partly rotating the shafts *4*, *4'*, being adapted to close together along their lower or free longitudinal edges or members so as to form a V-shaped hopper *c* beneath the 15 opening *2*. Immediately beneath the hopper *c* thus formed and extending longitudinally through the car between the shafts *4*, *4'*, is a shaft *5* rotatable in bearings *6* fixed to the car *a*, and on the shaft *5* is 20 fixed a balanced door or chute *d* of suitable width and preferably corresponding in length to the doors *b* and openings *2*, the balanced door or chute *d*, when horizontal, being adapted to bear longitudinally at its 25 middle portion or thereabout, against the lower free edges or members of the doors *b* and thereby hold or lock the latter in their closed position, as shown particularly in Fig. 2, and to be moved transversely 30 thereat about the said edges radially to the axial bearings *6* of the shaft *5* for releasing and allowing either of the doors *b* to be opened and the other door *b* held closed as hereinafter more particularly referred to. 35 In the arrangement of the several parts of our improved door operating mechanism relatively to each other as we shall now proceed to describe reference is particularly made to Fig. 2 in which the said 40 parts are in their normal position with the doors closed and locked.

On the shaft *4*, preferably outside the end 7 of the car *a*, is fixed at right angles to the face of the inside door *b*, an arm *8*, and on 45 the shaft *4'* at a suitable inclination to the face of the outside door *b*, is fixed an arm *8'* having its free end somewhat higher than the corresponding end of the arm *8*, and to the latter is coupled one end of a vertically arranged link *9* having its other end 50 coupled to the inner end of a horizontally arranged bar *10* which is coupled at its other end to the free end of the arm *8'*, the arms *8*, *8'*, link *9*, and bar *10* being preferably, in the same plane.

On the shaft *5* is fixed at a suitable inclination to the face of the balanced door or chute *d*, an arm *11* which inclines toward the arm *8* of the inside door *b* in a parallel 60 and preferably, outer plane thereto, and to the free end of the arm *11* is coupled one end of a horizontally arranged (or thereabout) link *12* which preferably, extends toward the arm *8'* of the outside door *b* 65 and is coupled at its free end to the lower

end of a lever *13* of the third kind (hereinafter referred to as the "controlling lever") which is fulcrumed or hinged at its upper end on a pin *14* mounted in a bracket *15* fixed to the car frame, the arm *11*, link *12*, and lever *13* being preferably, in the same plane.

In the inner face of the controlling lever 13, at a suitable distance from its fulcrum *14*, is formed a circular recess *16* (seen particularly in Fig. 6) in which is revolvably fitted a circular block *17* (hereinafter referred to as the "switch-block") which bears at its inner side against the bottom of the recess *16* and preferably, projects beyond the said face, the switch block *17* being formed on its inner side with a central circular shank or stem *17'* which projects therefrom through, and has its bearing in the lever *13*, and on the outer projecting part of the shank *17'* is fixed one end of a gravity lever *18* having preferably, a weight *18'* at its free end.

In the outer face of and corresponding in depth to the projecting portion of the switch-block *17* is formed a U-shaped recess *19* having its closed end concentric with the shank *17'*, and its sides parallel, the other end of the recess *19* being open and affording a free passage to and from the latter through the periphery of the projecting portion of the switch-block *17*, the recess *19* as seen in Figs. 5, 6, and 9, being vertical in its lowest position wherein it is held until otherwise constrained, by the gravity lever *18* which is also vertical in its lowest position and longitudinally co-incident with the recess *19* as shown.

On the inner face of the controlling lever *13* and corresponding in depth to that of the projecting portion of the switch-block *17* and its recess *19*, are formed two slotways *20* and *21* which are partway straight extending from their lower open ends upward and outward at opposite inclinations from the periphery of the projecting portion of the switch-block *17* where their adjacent sides meet, and thence curved upward to their upper closed ends, the center lines of the straight parts of the slotways *20*, *21*, being radial to the center of the switch-block *17*, and the center lines of the curved parts of the slotways *20*, *21*, being, when the said slotways are respectively, in operation (as hereinafter described) concentric with the pivot or fulcrum *22* of the horizontally arranged main operating lever *e* which is preferably, of the first kind having its pivot *22* mounted in a bracket *22'* fixed to the car frame as shown, the width of each slotway *20*, *21*, corresponding to that of the recess *19* in the switch-block *17*, so that when the latter with its shank *17'* is partially rotated by the gravity lever *18* in one direction, its recess *19* registers with the slot- 120 125 130

way 20, and in the other direction with the slotway 21.

On the front or outer face of the inner arm 23 of the operating lever *e* is pivoted a roller 24 which is diametrically somewhat less than, but practically the same as the width of the recess 19 and slotways 20, 21, the roller 24 being normally, in the closed position of the doors *b* and *d*, within the recess 19, and circumferentially in engagement with or bearing against the closed end of the latter, whereby the operating lever *e* and controlling lever 13 are interlocked and inoperative.

On the outer face of the controlling lever 13 at a suitable distance above the switch-block 17 is a projection 25 having its opposite ends so shaped that when the switch-block 17 is partly rotated as before mentioned, by the gravity lever 18, in either direction for registering the recess 19 with either of the slotways 20, 21, the corresponding end of the projection 25 operates as a stop to the gravity lever 18 and thereby indicates the position of the recess 19 relatively to the slotways 20, 21. For locking the switch-block 17 in either of the said positions of its recess 19 relatively to the slotways 20, 21, we preferably, use a lever 26 of the first kind which is pivoted on a pin fixed to, and projecting from the inner face of the controlling lever 13 adjacent to the switch-block 17, the outer arm of the lever 26 being weighted and its inner arm formed with an upwardly projecting tooth 27, (see particularly in Figs. 7 and 11) which, on the partial rotation of the switch-block 17, to the right by the gravity lever 18 for registering its recess 19 with the slotway 20, engages in a notch 20' formed transversely in the periphery of the switch-block 17 within its recess 16, as seen in Figs. 8 and 10, whereby the switch-block 17 is locked, while, on partially rotating the switch-block 17 in the opposite direction for registering the recess 19 with the slotway 21, the tooth 27 engages in a notch 21' formed transversely in the said periphery at the proper distance from the notch 20' and correspondingly locks the switch-block 17.

From the inner side of the locking lever 26 adjacent to the tooth 27 and in the direction of the operating lever *e* projects a horizontally arranged stud or pin 26' (seen particularly in Figs. 7 and 11) on which is pivoted a vertically arranged gravity trip lever 27' preferably, of the first kind, having the free end *y* of its upper arm somewhat higher than the tooth 27 of the lever 26, and curved radially to its pivoted center *x*, for engaging the bottom edge of the arm 23 of the operating lever *e*, the lower arm of the lever 27' being weighted, whereby, on the return of the arm 23 along either slotway 20, 21, the bottom edge of the arm 23

will strike the upper end of the lever 27' and thereby force downward the inner arm of the locking lever 26 and automatically disengage its tooth 27 from the switch-block 17, when the gravity lever 18 automatically descends and returns the switch-block 17 to its normal position.

The inner arm 23 of the operating lever *e* is engaged at its free end by, and movable with a crosshead or block 28 fixed to the piston-rod 29 of a piston (not shown) contained within a preferably, overhead upright cylinder *f* fixed to the car frame, and adapted to be raised and lowered therein by compressed air, steam, or other motive fluid supplied to the cylinder *f* from any available source and by any well-known means, the piston-rod 29 (or its extension 29' as shown in the present case) below the crosshead 28, being adapted preferably, to slide through a suitable guide 30 fixed to the car frame as shown.

The outer arm 31 of the operating lever *e* is coupled at its free end to the upper end of a vertically arranged double link *g* which is jointed at its lower end to the bar 10, preferably, midway between the coupled ends of the latter to the arm 8' and link 9, the link *g* being made preferably, in two equal lengths 32, 32', hinged together at their meeting ends by a pin 33. To the upper length 32 of the link *g* at a suitable distance from its junction with the arm 31 of the operating lever *e*, is coupled one end of a link 34 having its other end hinged to a bracket 35 fixed to the car frame, the lever *e*, and links *g* and 34, being preferably, in the plane of the bar 10.

In operation, assuming the doors *b* and *d* to be in their normal position or closed, with the several parts of their operating mechanism locked by the engagement of the roller 24 and switch-block 17 of the operating and controlling levers *e* and 13 respectively, as seen in Fig. 2, and it being desired to open the outside door *b* for discharging the contents of the car *a* through the opening 2 to the corresponding side thereof beneath the car *a*, the trip lever 27' being first thrown out of engagement with the lever *e*, the switch-block 17 is partly rotated to the right by the gravity lever 18 until the recess 19 of the switch-block 17 registers with the slotway 20 as indicated by the stoppage of the gravity lever 18 by the corresponding right hand end of the projection 25 on the lever 13, in which position the switch-block 17 is then automatically locked by the lever 26, thereby allowing free passage to the roller 24 along the recess 19 and slotway 20. Air being then admitted to the cylinder *f* beneath the piston therein, the latter with the piston-rod 29 and crosshead 28 is thereby raised and correspondingly raises the inner arm 23 of the operating lever *e*, which

causes the roller 24 to travel along the recess 19 of the switch-block 17 and the inclined straight part of the slotway 20, and in so doing constrains the controlling lever 13 to be moved to the left, as indicated by the arrow in Fig. 3, radially about its fulcrum 14, whereby the link 12 which couples the lower end of the lever 13 to the arm 11 pulls the latter to the left, or so as to swing the balanced door or chute *d* to the right about its shaft 5 into the open position against the underside of the inside door *b* as seen in Fig. 3, thereby releasing and allowing the outside door *b* to be opened and at the same time holding the inside door *b* closed. Meantime, by the lowering of the outer arm 31 of the operating lever *e*, a downward pressure is imparted to the link *g*, but, owing to the outside door *b* being held closed by the balanced door or chute *d* until the latter is fully opened and clear of the outside door *b* as seen in Fig. 3, the arms 8, 8', of the doors *b* remain rigid so that the bar 10 and link 9 are unaffected by the said pressure on the link *g* but remain normal as in Fig. 2, whereby the link 34 is constrained downward about its fulcrum 35 so as to force the two lengths 32, 32', of the link *g* to the right out of their normal alignment as seen in Fig. 3, until, on the roller 24 of the operating lever *e* entering and traveling along the curved part of the slotway 20, which in this position of the controlling lever 13, is concentric with the fulcrum 22 of the operating lever *e*, there is no further movement of the controlling lever 13; but by the continued downward movement of the operating lever *e* in obedience to the upward movement of the piston within the cylinder *f*, the two lengths 32, 32', of the link *g*, owing to the descent of the length 32 at its junction with the arm 31 and link 34 being in opposite arcs, are returned to their normal alignment and with the bar 10 and link 9 are constrained about the arm 8 of the inside door *b* as a fixed point or fulcrum, into the relative positions seen in Fig. 4, or so as to throw the arm 8', and with it the outside door *b*, downward about the shaft 4' at an accelerated speed into the open position of the outside door *b* which thereby forms with the balanced door *d* and the inside door *b* a chute for directing the contents of the car *a* discharged through the opening 2 to the side of the car *a*.

For closing the outside door *b*, and balanced door or chute *d*, air is admitted within the cylinder *f* above the piston, which lowers the inner arm 23 and raises the outer arm 31 of the operating lever *e*, whereby the roller 24 is returned along the curved part of the slotway 20, and while so doing, the outer arm 31 of the lever *e* returns the links *g* and 34, with the bar 10, link 9, and

arm 8', to their original position as seen in Fig. 3, or so as to close the outside door *b*, when the roller 24 entering and returning along the straight part of the slotway 20 into the recess 19 of the switch-block 17, constrains the controlling lever 13 to the left, or into its normal position as seen in Fig. 2, and in so doing pulls back the arm 11 and balanced door or chute *d* into their original position for locking the doors *b*. The locking lever 26 being now released by the descending arm 23 of the lever *e*, from engagement with the switch-block 17, the latter with the recess 19 is automatically returned by the descent of the gravity lever 18 to its normal position, or with the operating lever *e* and controlling lever 13, and other parts of the mechanism locked and inoperative as in Fig. 2.

Conversely, for opening the inside door *b* and swinging the balanced door or chute *d* over against the underside of the outside door *b* for dumping the material beneath the middle of the car *a*, the switch-block 17 is partly rotated to the left by the gravity lever 18 until its recess 19 registers with the straight part of the slotway 21 as indicated by the stoppage of the gravity lever 18 by the corresponding left hand end of the projection 25 on the lever 13, thereby allowing free passage to the roller 24 along the recess 19 and slotway 21. Air being then admitted to the cylinder *f* below the piston, the roller 24 travels along the recess 19 and the straight part of the slotway 21, and in so doing constrains the controlling lever 13 to be moved to the right, or in the direction of the dotted arrow in Fig. 3, radially about its fulcrum 14, whereby the link 12 which couples the lower end of the lever 13 to the arm 11 pushes the latter to the right, or so as to swing the balanced door or chute *d* over to the left about the shaft 5 into its open position against the underside of the outside door *b* thereby releasing and allowing the inside door *b* to be opened and at the same time holding the outside door *b* closed; otherwise, the operation of the several parts of the mechanism in opening the inside door *b* is similar in every respect to that previously described for opening the outside door *b* and therefore needs no further description, except that, when opening the inside door *b* the links *g* and 34, with the bar 10 and link 9, are constrained about the arm 8' as a fixed point or fulcrum in lieu of the arm 8 as described when opening the outside door *b*.

We do not limit ourselves to the particular arrangement, form, or proportions of the several parts of our improved door operating mechanism as hereinbefore described it being obvious that these may be varied according to circumstances without depart-

ture from the essential principle of our invention, to wit, positively opening either of the side doors *b* subsequently to, and positively closing it in advance of the balanced 5 door or chute *d*.

What we claim as our invention and desire to secure by Letters Patent is:—

1. In a dump-car or analogous receptacle having a discharge opening, two opposite pivoted side doors adapted to open and close the said opening, a balanced door adapted to hold the side doors closed, means for positively opening the balanced door and subsequently positively opening either of the side 10 doors, and for positively closing the said opened side door, and subsequently positively closing the balanced door.
2. In a dump-car or analogous receptacle having a discharge opening, two opposite pivoted side doors adapted to open and close the said opening, a balanced door adapted to hold the side doors closed, means for positively opening the balanced door and subsequently positively opening either of the side 15 doors, and for positively closing the said opened side door and subsequently closing the balanced door, and means for automati- 20
- 25

cally locking the said doors in their closed position.

3. In a dump-car or analogous receptacle 30 having a discharge opening, two opposite pivoted side doors adapted to open and close the said opening, a balanced door adapted to hold the side doors closed, determinative means for positively opening the balanced 35 door in either of two opposite directions and thereby releasing one of the side doors, and subsequently positively opening the released side door, and means for locking the said determinative means in their determined 40 position.

4. In a dump-car or analogous receptacle having a discharge opening, two opposite pivoted side doors adapted to open and close the said opening, a balanced door adapted to 45 hold the side doors closed, means for positively closing either of the side doors and subsequently positively closing the balanced door.
